SHELVING STRUCTURE

Mario Roggero, Genova-Sestri, Italy, assignor to
Pier Carlo Ricchiardi, Rome, Italy

Application May 23, 1946, Serial No. 671,712

16 Claims. (Cl. 211—143)

1

This invention relates to articles of furniture and more particularly to shelving structures having superimposed shelving sections.

An object of the invention is to provide a shelving structure, wherein the upper movable shelving section may be readily lowered or lifted without any angular shifting or swinging thereof.

Another object of the invention is to arrange track-forming elements for the movable shelving section as well as the counterweights connected with said movable shelving section in such a manner, that they do not occupy useful space within the shelving structure and do not affect the outer appearance thereof.

Other objects and advantages will be apparent from the following specification when read in conjunction with the accompanying drawings forming part of this specification, wherein:

Fig. 1 is a perspective view of a shelving structure according to the invention, which is provided with a series of movable shelving sections normally superimposed over a series of stationary shelving sections, and which includes a mechanism for displacing the movable shelving sections downwardly in front of the stationary shelving sections;

Figure 2 illustrates diagrammatically, in side elevation, the arrangement of guides and other elements of the shelving structure according to Fig. 1 for displacing the upper movable shelving section;

Figs. 2a and 2b are fragmentary diagrammatical views, similar to that shown in Fig. 2, illustrating the upper movable shelving section in two different positions;

Figure 3 is a diagrammatic view of another embodiment of the invention, and

Figure 4 illustrates an engaging roller of the movable shelving section in engagement with a track-forming member of the structure.

According to the invention, an article of furniture, e. g. a shelving structure as shown in Figure 1, may comprise a number of elementary shelves composed of a lower fixed part or stationary shelving section M and an upper part or movable shelving section F superimposed to the lower one and connected to said lower part by a mechanism rendering possible an easy lowering of the movable shelving section F from its upper position shown in full lines in Fig. 2 into a lowered position F' shown in dash and dot lines in said Fig. 2 by a pull on one of the handles H attached to the bottom part of the movable sections F. Of course, as will be better seen hereinafter, by the same mechanism it is possible

2

to return, with the same easiness, the movable shelving sections from the position indicated by F' into the position F.

As shown at the right-hand side of Figure 1, the shelves may be protected by shutters or the like A, hinged or otherwise connected to the stationary frame of the shelving structure.

According to the invention, the said mechanism comprises for each movable shelving section F' a number (preferably a pair) of fixed guides or stationary track-forming means G (Figures 1 to 3) attached to the fixed piece of furniture M (or in the case of a shelving structure as shown in Figure 1, to the frame of the stationary shelving sections) and projecting upwardly to a height substantially corresponding to the height of the upper shelves F. Each of said guides G comprises a substantially straight vertical portion 10, a substantially straight horizontal portion 12 and an intermediate curved portion 14 connecting, without forming any sharp angle, said vertical front portion 10 and said horizontal upper portion 12. The vertical front portion 10 arranged substantially parallel and near to the front upright members of the side frames projects downwardly to a suitable point and extends upwardly substantially to the height of the top of the movable shelving section F when the latter is in its upper position. The upper horizontal portion 12 extends forwardly from the rear end of the frame of the shelving structure, and the intermediate curved portion 14 may be considered as the rounding off of the angle formed by said vertical and horizontal portions.

On the other hand a complementary guide member G' is arranged on each side of the movable shelving section F. According to the embodiment shown in Figs. 2, 2a, 2b, said guiding means G' is formed by members of the frame of the movable shelving section F. Said guiding means G' comprises a lower substantially horizontal portion 16 extending rearwardly from the front of the movable shelving section F, a curved portion 18 being a continuation of said lower portion 16 and a rear substantially vertical portion 20 extending upwardly and being a continuation of said curved portion 18. The lower portion 16 of the guiding means G' is substantially parallel to the upper portion 12 of the stationary track-forming means G; the curve of the curved portion 18 of the guiding means G' is similar, reversed and inverted relative to the curve of the curved portion 14 of the stationary track forming means G (according to the embodiment shown in

Figs. 2, 2a and 2b, said curved portions 18 and 14 respectively are represented by arcs with the radius R' and R respectively; and the rear portion 20 of the guiding means G' is substantially parallel to the front portion 10 of the track-forming means G.

The guiding means G' arranged on the movable shelving section F are arranged for cooperation with supporting rollers P (only one being shown) rotatably arranged at a fixed point at the front of the shelving structure adjacent to the front portions 10 of the stationary track-forming means G. Said supporting rollers P being in rolling engagement with said guiding means G' support the movable shelving section F during their engagement with the lower portion 16 of said guiding means.

In the embodiment shown in Figs. 2 and 4, the stationary track-forming means G are made of a hollow tubular member having a longitudinally extending slot 22. Furthermore, for a purpose to be described hereinafter, each hollow front portion 10 of the tubular stationary track-forming means G is provided with a notch or cut-out 24 communicating with the interior of said hollow front portion.

On each side of the movable shelving section F an upper engaging roller B is rotatably mounted on a shaft at the upper rear portion of said movable shelving section F. The shaft carrying the engaging roller B extends through the slot 22 of the hollow tubular track-forming means G into the interior of the latter so that the engaging roller B cooperating with the stationary track-forming means may ride within the latter.

Moreover, on each side of the movable shelving section F a lower engaging roller B' is rotatably arranged at the lower rear portion of said movable shelving section remote from the upper engaging roller B. A line drawn to connect the axes of said rollers B and B' with each other is parallel to the front portion 10 of the stationary track-forming means G'.

As will be apparent from above, when the movable shelving section F is superimposed over the stationary shelving section M as shown in full lines in Fig. 2, the upper engaging roller B of the movable shelving section is in engagement with the rear end of the upper horizontal portion 12 of the stationary track-forming means G and the supporting roller P is in engagement with the front end of the lower portion 16 of the guiding means G' arranged on the movable shelving section F.

When it is desired to lower the movable shelving section F from its upper position shown in full lines in Fig. 2 into a lower position F' shown in dash and dot lines in said Fig. 2, the movable shelving section is gripped by hand at the handle H and, at first, is pulled outwardly. During said outward movement of the movable shelving section F, the upper engaging roller B rides along the horizontal portion 12 of the stationary track-forming means G until it reaches the position shown in Fig. 2a, whereupon it enters the curved portion 14 and rides along the latter until it reaches the position shown in Fig. 2b. At the same time, the lower portion of the movable shelving section F is supported and guided by the supporting roller P cooperating at first with the lower portion 16 of the guiding means G' and thereafter with the curved portion 18 of the latter.

Moreover, shortly before the movable shelving section F reaches the position shown in Fig. 2b, its lower engaging roller B' enters the front por-

tion 16 of the stationary track-forming means through the notch 24 for engagement with the latter.

Then, the movable shelving section F may be moved downwardly from the position shown in Fig. 2b into the position F' shown in dash and dot lines in Fig. 2. During said downward movement both engaging rollers B and B' ride along the vertical front portion 10 of the stationary track-forming means G.

In the lower position F', the movable shelving section is suspended from the front portion 10 of the stationary track-forming means G in the manner of a cantilever.

For a return of the movable shelving section from the lower position F' (Fig. 2) into its upper position F (Fig. 2) above described steps are taken in reversed order.

As mentioned above, the portions 12 and 16 of the stationary track-forming means G and guiding means G' respectively are parallel to each other, the portions 10 and 20 of said track-forming means and guiding means are likewise parallel to each other and the curve of the curved portion 18 of the guiding means G' is similar, reversed and inverted relative to the curve of the curved portion 14 of the track-forming means G. Therefore, during above described displacement of the movable shelving section F the latter is always moved parallel to itself, also when guided along a curved path. In Figs. 2 and 2a K' indicates the path of roller B'; in Fig. 2a K indicates the path of a point of the movable shelving section F near the handle H. The parallel movement of the movable shelving section F is a characteristic feature of the guiding mechanism according to the invention which will be referred to hereinafter as the "reverse guides."

In order to facilitate the displacement of the movable shelving section, preferably a counterweight W is connected thereto. As shown in Figure 3, to the lower part of the shiftable shelving section F, flexible connecting means L such as a line, strap, band or the like, (or even a pair or a number of such flexible connecting means) is attached which may run over the supporting roller P and an idling roller P' journaled at the rear of the shelving structure and carries at its lower end a weight W which, during the shifting of the shelving section F', runs along the rear part of the fixed piece of furniture M. When the upper shelving section F is moved substantially from the position shown in Fig. 2b into the position shown in full lines in Fig. 2, the weight W passes rearwardly of a lower guide pulley P'', rolls or slides along an inclined guideway C and comes to rest near the front bottom part or socket Z of the lower furniture. Thus, when the upper movable shelving section F' is superimposed over the stationary shelving section M the counterweight is inoperative and when the upper movable shelving section is first pulled outwardly, the operator does not need to lift the counterweight, and during the first part of the downward path he needs only to shift same along the bottom of the inclined guideway C. When on the contrary the movable shelving section tends to slide downwardly on the straight front portion 10 of the stationary track-forming means G, the counterweight is gradually lifted first along the ascending portion of the guideway C and at the end of the curved path said weight W comes to be freely suspended, so that it approximately balances the load of the movable shelving section, which is now suspended from the

front portion 10 of the track-forming means G by means of the spaced rollers B and B'.

According to the embodiment shown in Figure 3, the pairs of engaging rollers B and B' are mounted on brackets secured to the movable shelving section F, so that the straight rear portion of the guiding means G' is at a distance from the straight front portion of the track-forming means when the shelving section F is suspended from the latter. The roller B' may leave or enter the interior of the hollow tubular track-forming means through a slot 24. It is apparent that the above roller pairs B, B' co-operating with the stationary track-forming means G avoid any angular shifting of the movable shelving section F obliging same to remain always in true upright position, and be always displaced parallel to itself.

It is to be noted that in Figure 3 the weight W is simply attached to the line L or the like through a coiled spring S so that when the weight W reaches its lower position (which takes place when the upper piece of furniture has reached its upper level) it simply bears on the ground, while the spring S by recoiling keeps the line L sufficiently tight to avoid of same running off the sheaves or rollers P', or otherwise running out of the guide members. On the other hand, when the upper piece of furniture is pulled out, the spring remains in its coiled position and begins to uncoil only at the end of the horizontal path, during the shifting along of the curved guide part and the weight W is lifted only when the said piece of furniture is pulled down, at the end of its curved path.

It is apparent that the invention may be embodied in many different ways always based on the principle of the reversed guides, which might have a different shape, provided the fixed guide be made symmetrical to the movable one and the different straight guide branches be connected together by curved parts of suitably ample radii.

What I claim is:

1. A shelving structure comprising in combination: stationary track-forming means for connection with a support, said stationary track-forming means including an upper portion extending forwardly from the rear of said shelving structure and a front portion being a continuation of said upper portion and extending downwardly, supporting means fixedly disposed at the front of said shelving structure in a plane below the plane of said upper portion of the stationary track-forming means, a movable shelving section, engaging means mounted at the rear upper portion of said movable shelving section and cooperatively and shiftably engaged with said stationary track-forming means, and guiding means arranged on said movable shelving section, said guiding means including a lower portion extending rearwardly from the front of said shelving section and a rear portion being a continuation of said lower portion and extending upwardly, said lower portion of said guiding means being substantially parallel to said upper portion of said track-forming means, said rear portion of said guiding means being substantially parallel to said front portion of said track-forming means, and said supporting means being in cooperative and shiftable engagement with said guiding means.

2. In a shelving structure as claimed in claim 1, said stationary track-forming means being made

of a hollow tubular member having a longitudinally extending slot, and said engaging means extending through said slot and riding within said tubular member.

3. In a shelving structure as claimed in claim 1, said supporting means being in the shape of at least one roller rotatably mounted on a stationary point of the shelving structure.

4. In combination with a shelving structure as claimed in claim 1, a counter-weight, and means connecting said counter-weight to said movable shelving section.

5. In combination with a shelving structure as claimed in claim 1, a counter-weight, and means connecting said counter-weight to said movable shelving section, said counter-weight connection including means rendering the counter-weight substantially ineffective during the engagement of said engaging means with the forwardly extending upper portion of said stationary track-forming means.

6. In a shelving structure as claimed in claim 1, said supporting means being in the shape of at least one supporting roller rotatably mounted on a stationary point of the shelving structure, a counter-weight, and flexible connecting means connected to said counter-weight and to said movable shelving section, said flexible connecting means being engaged with said supporting roller.

7. A shelving structure comprising in combination: stationary track-forming means for connection with a support, said stationary track-forming means including a substantially straight upper portion extending forwardly from the rear of said shelving structure, a curved portion being a continuation of said upper portion and a substantially straight front portion being a continuation of said curved portion and extending downwardly, supporting means fixedly disposed at the front of said shelving structure in a plane below the plane of said upper portion of the stationary track-forming means, a movable shelving section, engaging means mounted at the rear upper portion of said movable shelving section and cooperatively and shiftably engaged with said stationary track-forming means, and guiding means arranged on said movable shelving section, said guiding means including a substantially straight lower portion extending rearwardly from the front of said shelving section, a curved portion being a continuation of said lower portion and a substantially straight rear portion being a continuation of said curved portion and extending upwardly, said lower portion of said guiding means being substantially parallel to said upper portion of said track-forming means, the curve of said curved portion of said guiding means being similar, reversed and inverted relative to the curve of said curved portion of said track-forming means, said rear portion of said guiding means being substantially parallel to said front portion of said track-forming means, and said supporting means being in cooperative and shiftable engagement with said guiding means and supporting said movable shelving section during an engagement with the lower portion of said guiding means.

8. In a shelving structure as claimed in claim 7, said supporting means being arranged adjacent the straight front portion of said stationary track-forming means.

9. A shelving structure comprising in combination: stationary track-forming means for connection with a support, said stationary track-

forming means including an upper portion extending forwardly from the rear of said shelving structure and a front portion being a continuation of said upper portion and extending downwardly, supporting means fixedly disposed at the front of said shelving structure in a plane below the plane of said upper portion of the stationary track-forming means, a movable shelving section, first engaging means mounted at the rear upper portion of said movable shelving section and cooperatively and shiftably engaged with said stationary track-forming means, guiding means arranged on said movable shelving section, said guiding means including a lower portion extending rearwardly from the front of said shelving section and a rear portion being a continuation of said lower portion and extending upwardly, said lower portion of said guiding means being substantially parallel to said upper portion of said track-forming means, said rear portion of said guiding means being substantially parallel to said front portion of said track-forming means, said supporting means being in cooperative and shiftable engagement with at least the lower portion of said guiding means and supporting said movable shelving section during an engagement with the lower portion of said guiding means, and second engaging means mounted at the rear lower portion of said movable shelving section, said second engaging means being arranged below and remote from said first engaging means and being capable of cooperative and shiftable engagement with the front portion of said stationary track-forming means when said first engaging means engages said front portion of the track-forming means.

10. In a shelving structure as claimed in claim 9, said stationary track-forming means being made of a hollow tubular member having a longitudinally extending slot, said first engaging means extending through said slot and riding within said tubular member, and said hollow tubular member having a notch communicating with its interior, said notch serving as a passage for said second engaging means so as to enable same to ride within said tubular member.

11. A shelving structure comprising in combination: stationary track-forming means for connection with a support, said stationary track-forming means including a substantially straight upper portion extending forwardly from the rear of said shelving structure, a curved portion being a continuation of said upper portion and a substantially straight front portion being a continuation of said curved portion and extending downwardly, supporting means fixedly disposed at the front of said shelving structure in a plane below the plane of said upper portion of the stationary track-forming means, a movable shelving section, first engaging means mounted at the rear upper portion of said movable shelving section and cooperatively and shiftably engaged with said stationary track-forming means, guiding means secured to said movable shelving section, said guiding means including a substantially straight lower portion extending rearwardly from the front of said shelving section, a curved portion being a continuation of said lower portion and a substantially straight rear portion being a continuation of said curved portion and extending upwardly, said lower portion of said guiding means being substantially parallel to said upper portion of said track-forming means, the curve of said curved portion of said guiding means being similar, reversed and inverted relative to the curve

of said curved portion of said track-forming means, said rear portion of said guiding means being substantially parallel to said front portion of said track-forming means, said supporting means being in cooperative and shiftable engagement with at least the lower portion of said guiding means and supporting said movable shelving section during an engagement with the lower portion of said guiding means, and second engaging means mounted at the rear lower portion of said movable shelving section, said second engaging means being arranged below and remote from said first engaging means and being capable of cooperative and shiftable engagement with the front portion of said stationary track-forming means when said first engaging means engages said front portion of the track-forming means.

12. In a shelving structure as claimed in claim 11, said stationary track-forming means being made of a hollow tubular member having a longitudinally extending slot, said first engaging means extending through said slot and riding within said tubular member, and said hollow tubular member having a notch communicating with its interior, said notch serving as a passage for said second engaging means so as to enable same to ride within said tubular member.

13. In a shelving structure as claimed in claim 1, a frame constituting said support connected with said stationary track-forming means, and a stationary shelving section arranged in the lower portion of said frame, the upper portion of said track-forming means being arranged above said stationary shelving section and extending forwardly from the rear of the shelving structure beyond the plane of the front of the stationary shelving section, and said movable shelving section being superimposed over said stationary shelving section when its engaging means is in engagement with the rear end of said upper portion of the track-forming means.

14. In a shelving structure as claimed in claim 7, a frame constituting said support connected with said stationary track-forming means, and a stationary shelving section arranged in the lower portion of said frame, the upper portion of said track-forming means being arranged above said stationary shelving section, said upper portion and the curved portion of the track-forming means extending forwardly from the rear of the shelving structure beyond the plane of the front of the stationary shelving section, and said movable shelving section being superimposed over said stationary shelving section when its engaging means is in engagement with the rear end of said upper portion of the track-forming means.

15. In a shelving structure as claimed in claim 9, a frame constituting said support connected with said stationary track-forming means, and a stationary shelving section arranged in the lower portion of said frame, the upper portion of said track-forming means being arranged above said stationary shelving section and extending forwardly from the rear of the shelving structure beyond the plane of the front of the stationary shelving section, and said movable shelving section being superimposed over said stationary shelving section when its first engaging means is in engagement with the rear end of said upper portion of the track-forming means.

16. In a shelving structure as claimed in claim 11, a frame constituting said support connected with said stationary track-forming means, and a stationary shelving section arranged in the lower portion of said frame, the upper portion of said

track-forming means being arranged above said stationary shelving section, said upper portion and the curved portion of the track-forming means extending forwardly from the rear of the shelving structure beyond the plane of the front of the stationary shelving section, and said movable shelving section being superimposed over said stationary shelving section when its first engaging means is in engagement with the rear end of said upper portion of the track-forming means. 10
